Fig. 3.

Fig. 6.

FIG. 1 is a perspective view of a dispensing container showing my new design with an extendible closure in an opened position;

FIG. 2 is a perspective view similar to that of FIG. 1, except that the closure is in a closed position;

FIG. 3 is a side elevational view with the closure in a closed position;

FIG. 4 is a view similar to FIG. 3 except that the closure is in an opened position;

FIG. 5 is an elevational view looking from the right of FIG. 3; and

FIG. 6 is a top plan view.

The surface of the sides of the container opposite FIGS. 3 and 5 and the bottom surface are plain and unornamented.

I claim:

The ornamental design for a dispensing container, substantially as shown and described.
